(57) **CLAIM**

The ornamental design for an optical connector end-face cleaner, as shown and described.

DESCRIPTION

FIG. 1 is a perspective view of an optical connector end-face cleaner showing my design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof;

FIG. 8 is a front view thereof with its cap opened;

FIG. 9 is a perspective view of a second embodiment of an optical connector end-face cleaner;

FIG. 10 is a front view thereof;

FIG. 11 is a rear view thereof;

FIG. 12 is a right side view thereof;

FIG. 13 is a left side view thereof;

FIG. 14 is a top plan view thereof;

FIG. 15 is a bottom view thereof;

FIG. 16 is a front view thereof with its cleaning bar portion turned; and,

FIG. 17 is a front view of a third embodiment of an optical connector end-face cleaner.
